DRYING APPARATUS FOR PLATES OF METAL AND OTHER MATERIAL

Application filed September 14, 1925. Serial No. 56,120.

This invention relates to improvements in drying apparatus for plates of metal and other material.

One of the objects of this invention is to economize the space usually required to mount drying apparatus for the purpose specified.

Another object of our invention is to enable a relatively large number of coated or painted plates to be carried in a horizontal position through a drying atmosphere for an interval of time sufficient to permit the coating material which when applied is frequently uneven and lumpy to flow or spread evenly and in all directions over the entire surface and thus to prevent such coating material from flowing or running in one direction over the edges of the plates.

Another object of our invention is to enable wet plates to be elevated in horizontal position with a wet face uppermost and thereafter be shifted to descend also in horizontal position with the same face uppermost whereby drying of the uppermost face may be accomplished during the elevation and descent of the plates without any danger of "running" of the coating material in one direction.

Still another object of our invention is to provide a plate elevating apparatus in which the plate-carriers are mounted to have intermittent movement to permit the feeding, transfer or shifting and delivery in horizontal position of the plate to the carriers.

Still another object of our invention comprises the provision in a plate drying apparatus of vertically-disposed elevating mechanism having ascending and descending plate-carrying stretches and the transfer or shifting of a plate from the ascending stretch to the descending stretch without turning the plate.

Another object of the invention is to utilize efficient means in the transfer of such plates which will enable shifting of a plate by engagement with the bottom surface thereof.

Still another object of our invention comprises the use in the handling of plates and the like of a roller having peripheral attracting means arranged to move or shift a plate upon rotation of the roller.

Still another object of our invention is the use of an electro-magnetic means for shifting the plates laterally from ascending to descending carriers.

Still another object of our invention is to provide in an elevating and descending apparatus means at the upper end thereof for engaging a plate holder to maintain the same in stationary position during the operation of transfer means.

Still another object of the invention is to provide means for automatically stopping the machine in the event of the fouling movement of a plate and we preferably provide electro-magnetic means for accomplishing this result.

Another object of the invention is to enable feeding, delivery and shifting devices to be arranged in channels within the plate-carriers and for this purpose we provide plate-carriers comprising sectional plate-carriers composed of a series of sections providing channels or spaces therebetween.

Another object of the invention is to provide a mounting for plate carriers which will be extremely solid and rigid and will enable carrying of a relatively heavy metal plate with a plate-carrier having a free end.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a side elevation of an apparatus embodying our invention showing the outer casing in section;

Fig. 2 is a section on the line 2—2 of Fig. 3 looking in the direction of the arrow;

Fig. 3 is a section on the line 3—3 of Fig. 1 looking the direction of the arrow;

Fig. 4 is a section on the line 4—4 of Fig. 3 looking in the direction of the arrow, and illustrating our preferred form of retaining and shifting device;

Fig. 5 is a section on the line 5—5 of Fig. 3 showing the supporting bracket for the initial shifting and retaining devices;

Fig. 6 is a section on the line 6—6 of Fig. 5 illustrating the feeding and delivery devices;

Fig. 7 is a section on the line 7—7 of Fig. 2 illustrating our improved electro-magnetic plate shifting rollers;

Fig. 8 is an enlarged section on the line 8—8 of Fig. 7 showing the top of the drying carrier and the shifting device mounted thereat;

Fig. 9 is a section on the line 9—9 of Fig. 8 illustrating a connection between the electric source of supply and the magnetic rollers;

Fig. 10 is a section on the line 10—10 of Fig. 1 showing in section the operating dog and the magnetic means for throwing it out of mesh to stop the operation of the plate carrier;

Fig. 11 is a diagrammatic view of the electric devices and connections for operating the magnetic rollers and for automatically stopping the operation of the carrier in the event of displacement of a plate; and

Fig. 12 is a view partly in section on the line 12—12 of Fig. 6 and partly diagrammatic of the lower drive chains and sprockets.

Referring now to these drawings, which illustrate a preferred embodiment of our invention, our plate-drying apparatus embodies the following elements:

35   *Conveyor mechanism*

A pair of endless conveyor chains C, C' are mounted to extend vertically, the members of a pair being arranged in horizontally-spaced relationship to each other. Each of said pair of chains C, C' are continuous and are mounted at their lower ends on sprockets S, S' on a centrally-located shaft 1 supported, as shown, in a pair of spaced oppositely-arranged frame castings F supported by feet f resting on the floor. As illustrated, each of these frame castings F have centrally-located vertical-extensions F' to each of which are connected by bolts B² a pair of vertically-extending angle-bars B, B', the upper ends of opposite pairs of which bars adjustably support tracks T, T' on which the upper ends of the continuous chains C, C' are mounted and guided, said chains thus having arcuate portions at their upper and lower ends and rectilinear vertically-disposed ascending and descending stretches which preferably incline or taper from the lower mounting toward the upper mounting to compensate for any sagging in the lifting or carrying of their loads as hereinafter specified.

As illustrated, the lower end of the chains are mounted upon the sprockets S, S' which are fast upon the centrally-located shaft 1

journalled in bearings 1^a integrally cast in the frame. The opposite ends of the chains are mounted and guided to pass over the grooved support or track T, T' formed in castings 2, 2' adjustably supported on the upper ends of the angle-bars B, B'. As illustrated, the castings 2, 2' are mounted in openings in plates 3, 3' fastened to the upper ends of the angle-bars B, B', the said castings 2, 2' being clamped to the plates 3, 3' by the use of outer plates or castings 4, 4' by clamping bolts 5.

As illustrated, the chains C, C' comprise a series of links c connecting pivot pins c¹ on which are mounted spools or rollers c² and on their vertical ascending and descending stretches the rollers c² are guided within tracks formed by a fastening trackstrip b to each of the angle bars B, B' and applying at the outer side thereof a U-shaped bar 6 having a track portion, spaced from the trackstrip b to form a groove and contacting with the rollers at the side opposite to said strip. Each link of the chain has an outward extension comprising a bracket-plate on a pair of which bracket plates a channel bar 7 is supported to extend transversely between the pair of chains C, C'.

95   *The plate holders*

Each of these channel bars 7 has mounted thereon a sectional plate holder 8 composed of a plurality of sections 8^a spaced from each other to provide plate-handling channels 8^b.

In the embodiment shown, each plate holder comprises four sections 8^a each formed of single wire bent between its ends to form a plate supporting part and passing at their inner attaching ends through both flanges of the channel bar. The inner ends have heads 8^c riveted at one side of the inner flange and have a bend 8^d at the opposite side of the other flange so as to be firmly supported by such channel bars. These sectional plate carriers are thus free at their outer ends and are provided with spacing thimbles 8^e.

It will be apparent that when plate carriers are thus mounted upon a conveyor chain, they will extend horizontally on the ascending and descending stretches of the chains and that plates to be dried may be supported in horizontal position upon such ascending and descending stretches thus avoiding any "running" of the coating material during such vertical movement. Both the ascending and descending stretches are, as aforesaid, preferably guided in a slightly inclined or conical path so as to compensate for any normal sagging of the plate holders.

125   *The driving mechanism*

These chains C, C' are preferably driven with an intermittent motion for a purpose to be hereinafter more particularly specified. As illustrated, a ratchet wheel 9 is fast upon

the shaft 1 and is intermittently moved by a dog or pawl 10 having its free end engaging the teeth of the said ratchet wheel 9 and being, as illustrated, pivoted at 11 at the outer end of an arm 12 pivotally mounted upon the said shaft 1. The said pivoted arm 12 is engaged at its outer end by a pivoted link 13 of which is in turn pivoted to an operating rod 14 connected to a cam strap 15 operatively mounted upon a grooved cam disc 16 upon a power shaft 17 driven from any suitable source of power not shown and mounted in bearings 18, 18' on the frame F. It will be apparent that upon rotation of the power shaft 17 and cam disc 16 the connecting rod will be moved intermittently which in turn will rock the pawl or dog about the shaft 1 and cause the shaft 1 to be rotated by an intermittent movement, each tooth in the ratchet corresponding to a step in such intermittent movement. It is desirable to prevent any excessive or slipping movement of the said shaft 1, and for this purpose we mount, in cooperation with the pawl, a braking device comprising a disc or wheel 19 fixed on the same shaft 1 which is braked by a braking shoe 20 having a lined braking surface engaging the same and operated into braking relationship simultaneously with the completion of each step in the intermittent movement by means of an arm 21 adjustably fastened upon a bifurcated arm 22 engaging the shaft 17 and carrying on a stub shaft 23 a roller 24 engaging a cam wheel 25 fixed on the power shaft 17. The cams 16 and 25 are arranged to time the braking action of the shoe so as to stop any excessive or slipping movement of the ratchet wheel and shaft.

The feeding mechanism

The movement of the chains and sectional plate carriers about an arcuate guide such as the sprockets S, S' at the lower ends, causes the opening-up or spacing of the plate carriers 8 and we provide just below the beginning of the ascending stretch of the chain, a feeding mechanism.

This feeding mechanism may be driven from any suitable source of power and, as illustrated, comprises a series of three bracket arms 30 each mounted at one end adjacent to the outer end of the plate carriers and having its free end extending or projecting inwardly into the spaces or channels 8^b between the sectional plate-carriers 8, thus permitting a plate P to be moved thereon into the path of the plate carriers and into the normal elevating position of such plates on the carriers, thus to avoid any shifting of the plates after engagement thereof by the said sectional plate carriers 8.

It will be seen that the projection of these feeding arms into the channels between the sections of the plate carriers, in effect, pro-

duce an interlacing relationship therebetween; that the arms lie in planes parallel with the plate carrier sections and extend into juxtaposition with each other. As illustrated, the plates are fed on to the carriers by supporting the same upon a series of belts 31 mounted on suitable pulleys (not shown) at one end, at the opposite end upon pulleys 32 fixed on a shaft 33 journaled in bearing brackets 34 on the side of a frame and when the plate is carried forwardly, the under surface thereof is engaged by belts 35 supported at one end upon pulleys 36 also fixed upon the shaft 33 and supported at their opposite ends upon pulleys 30^b mounted on stub shafts 30^a at free ends of the bell-crank arms 30 which are rigidly supported upon rods 37 and 38 so as to hold the outer pulley-supporting free end of the arm firmly in position within the spaces or channels between said plate-carrier sections.

From the above, it will be obvious that a plate fed to the outer belts will be carried into the path of the plate-carriers just before the closing up for the ascending stretch thereof; that the plate will thus be supported in substantially horizontal position so that wet paint or a coating of any kind may be dried without any marring thereof by engagement of the plate-carriers with the upper wet face thereof and without any "running" of the paint or other material.

The transfer mechanism

It is desirable not only to carry the plates in horizontal position on the ascending stretch, but also to carry such plates on the downward or descending stretch of this chain with the same surface of the plate uppermost as it is apparent that if a plate were allowed to turn or swing around with the chain and plate carriers, they would first be turned edgewise and then turned over and to avoid this and to continue the drying on the downward stretch, we provide at the upper end of the conveyor mechanism a transfer mechanism for shifting the plate from the upper end of the ascending stretch to the beginning of the descending stretch and this shifting is accomplished between the end and beginning respectively of these stretches and the turning portion of the chains.

In order to provide space for the operation of the shifting mechanism we preferably cause the chains at the upper end to be first guided in a sharp curve between the vertically-disposed ascending portion and the beginning of the arcuate portion and we also provide a similar sharp guiding curve between said arcuate portion and the beginning of the descending stretch, thus causing an enlargement of the normal spacing or separation between the plate carriers to facilitate the shifting of a plate edgewise or horizontally from the end

of the ascending stretch to the beginning of the descending stretch.

The magnetic rollers

5 In the preferred embodiment shown, this shifting is accomplished by mounting at the upper end of the conveyor between the ascending and descending stretches of chain and carriers of self-attaching or self-attracting 10 means, preferably comprising magnetic rollers R for engaging the lower surfaces of the plates P and shifting the same edgewise laterally, in combination, with means for initially 15 shifting the plates into contact with said magnetic shifting rollers. As illustrated, these shifting devices comprise a pair of magnetic rollers R each mounted on a shaft 40 in bearing blocks 41, 41^a on the track castings T, T' just below the said guiding tracks and, 20 as illustrated, these magnetic rollers (see Figs. 3 and 7) are actuated to rotate in the same direction by providing on each of the shafts, sprockets 42 which are commonly or mutually engaged by a sprocket chain 43 25 which is driven from a shaft 44 having a sprocket 45 fixed thereon, over which the opposite end of the chain 43 passes. This shaft 44 has a sprocket 46 fast thereon and is in turn, driven through the chain 47 and 30 sprocket 48 on a shaft 49 which is geared or connected by a series of sprockets and chains with a drive-shaft 50 at the delivery end of the machine.

In said preferred form illustrated, a non-magnetic roller r is preferably mounted between the two magnetic rollers and, as shown, is so mounted between the magnetic rollers on a shaft 51 supported in a bearing bracket 52, 52' and is rotated by engagement of a 40 sprocket 53 with the actuating chain for the magnetic roller. Each roller is provided with annular collars 54 having peripheral surfaces 55 which are magnetized by windings or coils 56. Electric energy is supplied to said 45 rollers R by providing at one end thereof an insulated circular track 57 with which a contact brush 58 is supported in a holder 59 connected to the track casting T'. The brushes 58 are connected by wires 60 to one pole of the generator, and the magnetic windings or 50 coils 56 of the rollers are suitably grounded on the shaft which is connected, as represented in the diagrammatic view in Fig. 11 by the line 40^a and which is in turn connected to 55 the ground wire 40^b of the generator. The magnetic rollers, as shown, are each provided with a series of magnetic collars having peripheral contact surfaces and a series of coils are arranged between and electrically 60 connected with such collars. It will be obvious, therefore, that when these magnetic collars are energized, they will attract, grip and hold the under or lower surface of a metal plate and that when the roller is, during 65 such magnetic attraction, rotated, as

aforesaid, it will cause the plate to be shifted edgewise laterally; that contact of the edge of the plate with one of the rollers will thus cause an edgewise shifting over that roller and into contact with the second roller 70 which will continue to shift the same edgewise or laterally on to a plate carrier on the descending stretch of the conveyor chain.

In a shifting device of this type, we find that the momentum of a plate during movement over the rollers causes it to be shifted or slid beyond the surface of the last roller and on the plate carriers on the descending stretch of the conveyor chains.

In the said preferred embodiment, we preferably provide a series of buffer bars preferably comprising two spring buffer bars 61, 61^a mounted upon the bracket bar 62 supported upon cross bars 63, 63^a forming a portion of the upper end of the machine, and 85 between these two buffer bars 61, 61^a we preferably provide another flexible spring buffer bar 64 connected at opposite ends in an inclined position on a similar bracket bar 64^a 90 also supported upon said cross bar.

Our preferred means for initially shifting the plate into engagement with the magnetic rollers comprises a series of bracket arms 70 (see Fig. 3) extending within the spaces 8^b between the sectional plate carriers 8^a which arms are securely fastened at the outer ends at two points on the bars 71 and 72 mounted adjacent to the outer end of the plate-carriers in brackets 73 and 74 fastened to the cross bar 63^a and have sprockets 70^a on stub shafts 70^b at the free ends which extend to a point adjacent to the rollers R. The brackets have journalled at opposite ends thereof two shafts 75 and 76. On the shaft 75 are journalled sprockets 77 each having mounted thereon one end of a chain 78, the opposite end of which passes over a sprocket 70^a. Each chain preferably is provided with a tooth or projection 79 adapted in each revolution to engage the side edge of the plate and to move or slide it edgewise into contact with the magnetic rollers. The said shaft 75 is driven continuously and timed by a connection to the shaft 80. As shown, the shaft 75 is provided with a sprocket 75^a meshing with a chain 75^b which engages a sprocket 80^a on the shaft 80 which is geared by gears 80^b, 80^c to the shaft 44 from which the magnetic gears are rotated and which in turn is connected to the power shaft at the delivery side 110 of the machine.

In order to enable engagement of the tooth 79 with each of the plates to cause a shifting thereof, it is desirable to hold a plate holder 125 in a predetermined position, and for this purpose we provide a series of arms 81 preferably comprising one for each plate section and each provided at its free end with an engaging notch 81^a adapted to be swung later- 130

ally and intermittently into engagement with the sectional plate holders 8^a as the same approach the position at the end of the ascending stretch. As illustrated, these arms are oscillated to engage and disengage the plate holders by mounting such arms on the shaft 76 which is journaled in bearing brackets 74 and said shaft is provided at its outer end with a crank 82 which is connected to a vertical rod 83 extending downwardly and has a bifurcated lower end 83^a which straddles the drive shaft 17 and is rocked up and down by engagement of a roller 83^b carried on a stub shaft 83^c near the lower end of the rod 83 with a cam 84 fixed on said drive shaft 17. The rod 83 is thus rocked so as to intermittently oscillate the arms 81 into and out of engagement with the sectional plate holders 8^b.

20 The plates P after being shifted to the descending stretch or plait of plate-carriers, are carried downwardly until they engage and are supported upon delivery belts 90 similarly extending within the channels or 25 spaces 8^b between the sectional plate holders 8^a. These delivery belts are supported upon bell-crank bracket arms 91 mounted at the outer edge of the machine on rods 92 and 93. The inner ends of the delivery belts 90 are 30 each mounted upon a pulley 94 journaled upon a stub shaft 95 supported on the bracket arm 91 while the opposite outer end is mounted on pulleys 96 on a drive shaft 50 mounted in bearings 98 at opposite side edges 35 of the frame casting F of the machine. On this shaft 50 is also supported transfer pulleys 98 having chains 99 for movement of the plates outside of the machine, which chain is preferably provided with projections for 40 engaging the edges of the plate and in the preferred embodiment of the machine shown, said chain is connected with any suitable source of power not shown to supply power for driving the shaft 50.

45 On the shaft 50 is provided a large gear 100 which meshes with a pinion 101 to rotate the shaft of a generator 102 which furnishes energy to the magnetic rollers R and to the magnet for the stop mechanism hereinafter 50 specified. Said shaft 50 is also provided with a sprocket 103 which through the chain 104 and sprocket 105 transmits power to the shaft 33 at the feeding side of the machine for the 55 purpose of rotating the feed belts 31 which have heretofore been described.

Said shaft 50 also has mounted thereon a sprocket 106 which through the chain 107 drives a sprocket 108 on a stub shaft 109 60 on which shaft is mounted sprocket 110 driving through a chain 111 passing over a sprocket 112 on the stub shaft 49 on which stub shaft is mounted the sprocket 48 which drives the chain 47 engaging the sprocket 46 65 on the shaft 44 from which the magnetic

rollers and other devices hereinabove specified are driven.

The automatic stopping mechanism

We preferably provide means for automatically stopping the machine in the event of the fouling or displacement of a plate during the transfer or shifting thereof or in the event of the shifting means failing to operate.

For this purpose, we preferably mount over 70 the magnetic rollers R a movable guard plate 120 preferably pivoted at one end by pivot 121 in bearings 122 suitably supported on the bearing bracket for the magnetic roller

and being free at its opposite ends 120^a so as 75 to be engaged and moved in the event of the failure of the transfer or shifting mechanism to operate and thus to cause the plate-carriers to move a plate into engagement therewith or in case any other part of the mechanism 80 fails to properly move a plate in proper position.

When the end 120^a of the guard plate is so engaged by one of the plates P to be dried, it will be lifted and will engage a spring-pressed roller 123 which is mounted 85 upon a pin 124 movable vertically in a bracket 125 and the end of this pin 124 upon movement thereof will compress the spring 126 and will engage one of the contacts of a 90 switch 127 which will close the circuit and energize a magnet 128 (see Figs. 10 and 11) the armature 129 of which is pivotally mounted on a pivot 130 and has at its end a cushioning device comprising a plunger bar 131 hav-

ing a spring 132 abutting between a base 133 95 on the armature and a pin 134 through the shank thereof. When so energized, the pivoted armature will be rocked about its pivot and an extension 135 thereof at the opposite 100 side of the pivot will be caused to engage the dog or pawl 10 to lift the same out of engagement with the ratchet wheel 9 so as to prevent further intermittent rotation. The extension 135 will be held in elevated position with the 105 dog 10 out of engagement by means of a 110 spring-pressed arm 136 pivoted at 136^a on the magnet 128 and having a notch 136^b adapted to engage a projection or pin 137 on said extension 135. The armature 129 is normally held in elevated position by means of a spring 115 138 stretched between said extension 135 and a projection 139 on the core of a magnet. The cushioning plunger 131 on the armature provides a flexible means for disengaging the dog so that the operation of the stopping mag-

net which is likely to happen at any time will in the event of being unable to release the dog because of its engaging position, will tension the spring 132 which will thus release the said dog so soon as it reaches a position when it can be released. It will be understood that the dog when in engagement with the ratchet and in its operating movement, cannot be lifted, and in order to free the ratchet from the pawl it is necessary to wait until the pawl 120 125 130

starts on its return movement. If, therefore, a place is being fouled while the pawl is so engaged, the magnet will be energized and the armature will be operated to store the power in the spring 132 which will thereafter lift the dog so soon as it starts on its backward movement.

Suitable horizontally-disposed guide means are provided at the opposite sides of the delivery belts for moving the plates into position on the plate-carriers, and for this purpose we mount curved feed plates 140 at opposite sides of such belts.

We also preferably provide vertical buffer or guide bars 141 at opposite sides of the ascending flight of the carriers for the purpose of maintaining the same in sidewise alignment. As illustrated, we also provide two pairs of vertical guide bars 142 for the inner edges of the plate in case of displacement toward the conveyor chain and magnetic rollers, one pair being arranged to guide plates on the ascending stretch and the other pair to guide on the descending stretch. These bars 142, as illustrated, are mounted at their lower ends on projecting lugs 142^a fastened to cross bars 143 which are connected at their opposite ends to angle frame bars. The upper ends of the pairs of guide bars 142 preferably rest upon or are arranged closely adjacent to the peripheries of the magnetic rollers so as to act as guards against contact of the edges of the plate therewith before reaching the upper end of the flight.

Having described our invention, we claim:

1. Apparatus for drying wet plates embodying elevating mechanism suitably mounted and driven and having ascending and descending portions, elongated plate-supporting carriers having permanent connections at the edge at one side thereof with said elevating mechanism and being free at their opposite edges and carried with said elevating mechanism and through the entire cycle of movement of said elevating mechanism, and means located below the free ends of said plate carriers for shifting a supported plate edgewise into supporting contact with plate carriers on the descending portion of such mechanism, to cause the same bottom surface of the plate to be again engaged and said plate to descend in a horizontal position with the same face uppermost.

2. Apparatus for drying wet plates embodying elevating mechanism suitably mounted and driven and having ascending and descending portions, elongated plate-supporting carriers having permanent connections at the edge at one side thereof with said elevating mechanism and being free at their opposite edges and carried with said elevating mechanism and through the entire cycle of movement of said elevating mechanism, means adjacent to the top of the

ascending portion and below said free ends for shifting a supported plate edgewise in a direction from the free outer edge toward the said connection and into supporting contact with plate carriers on the descending portion of such mechanism, to cause the same bottom surface of the plate to be again engaged and said plate to descend in a horizontal position with the same face uppermost, means for delivering plates over said free edges to the said supporting carriers in substantially horizontal position, and means for discharging the plates over said free edges also in horizontal position.

3. Apparatus for drying wet plates embodying, in combination, a casing having suitable means for providing a drying atmosphere therein, conveyor-chain mechanism mounted on sprockets to extend substantially in a vertical direction within said casing and having ascending and descending stretches, a series of elongated plate carriers, each connected with said chain mechanism at one edge and having its opposite end free and movable to extend horizontally on said ascending and descending stretches to engage the bottom surfaces only of such plates and said plate carriers being also movable radially of the axis of rotation of the sprockets at the upper end of said conveyor-chain mechanism, and means at the upper end of the ascending stretch and below the free ends of said plate carriers for causing a plate to be shifted endwise from the plate carrier on the ascending stretch in a direction toward the connection thereof with the conveyor-chain mechanism to a plate carrier on the descending stretch.

4. Apparatus for drying wet plates embodying, in combination, a casing, conveyor chain mechanism mounted to extend vertically in said casing and to have vertically-disposed ascending and descending stretches and arcuate connection portions at the upper and lower ends, means at the upper end of the chain for causing sharp curves or bends in said chain between the ascending stretch and the upper arcuate connecting portion and between said arcuate portion and the descending stretch, plate-carriers mounted on said chain and shifting means mounted contiguous to one of said carriers for causing the plate to be shifted in the opening caused by said sharp bend from the ascending stretch to the opening caused by the sharp bend in the descending stretch.

5. Apparatus for drying wet plates, embodying, in combination, a casing having means for producing a drying atmosphere therein, conveyor-chain mechanism mounted in said casing to extend vertically and to have vertically-disposed ascending and descending stretches and arcuate connecting portions at the lower and upper ends, elongated plate carriers, each connected with said chain mechanism at one edge and having its

opposite end free, means for feeding a plate to said plate carriers at the beginning of the vertically-disposed ascending stretch, means located below the free ends of said plate carriers for shifting the plates at the end of the ascending stretch to the beginning of the descending stretch, and delivery means for causing said plates to be discharged from the machine at the lower end of the vertically-disposed portion of the descending stretch.

6. Apparatus for drying wet plates, embodying, in combination, a casing, a pair of conveyor chains mounted within said casing to extend vertically and having an ascending stretch, sectional plate-carriers mounted on said conveyor chains and means extending between the sections of said plate-carriers for shifting a wet plate edgewise at the upper end of said ascending stretch.

7. Apparatus for drying wet plates, embodying, in combination, a casing, a pair of conveyor chains having ascending and descending stretches, sectional plate carriers mounted on said chain, and means extending between the sections of the plate-carriers at the upper end of said ascending stretch for shifting a wet plate edgewise into engagement with plate-carriers on the descending stretch of the chains with the same face of the plate uppermost.

8. Apparatus for drying wet plates, embodying, in combination, a casing, a pair of conveyor chains having ascending and descending stretches, sectional plate-carriers mounted on said chain and means extending between the sections of the plate-carriers at the upper end of said ascending stretch for shifting a wet plate edgewise into engagement with a plate-carrier on the descending stretch of the chain with the same face uppermost, means for feeding a plate in horizontal position into engagement with the plate holders at the beginning of the ascending stretch and means for delivering and discharging said plate from plate-carriers at the end of the descending stretch.

9. Apparatus for drying wet plates, embodying, in combination, a casing, a pair of conveyor chains mounted to extend and move vertically in said casing, sectional plate-carriers mounted on said conveyor chains, means extending between the sections of the plate carriers for causing a plate to be moved edgewise substantially in horizontal position at the beginning of the vertically-disposed ascending stretch thereof to cause the bottom of the plate to be engaged by a plate-carrier during movement of such plate-carriers by the chain, means at the top of the ascending stretch also extending between the sections of the plate carriers for shifting said plates edgewise into engagement with plate-carriers on the descending stretch of the chain and means also extending between the sections of the plate carriers for delivering

said plates at the end of said descending stretch in substantially horizontal position.

10. Apparatus for drying wet plates embodying elevating mechanism suitably and driven to have intermittent movement and having ascending and descending stretches, elongated plate-supporting carriers having permanent connections at the edges at one side thereof with said elevating mechanism and being free at their opposite edges, said plate carriers being carried with said elevating mechanism through the entire cycle of movement thereof, and means located below the free ends of said plate carriers and movable synchronously with said elevating mechanism to shift a plate on said plate carriers from the ascending to the descending stretch of said mechanism during the stationary interval of said movement.

11. Apparatus for drying wet plates embodying elevating mechanism suitably mounted and driven to have intermittent movement and having ascending and descending stretches, elongated plate-supporting carriers having permanent connections at the edges at one side thereof with said elevating mechanism and being free at their opposite edges, said plate carriers being carried with said elevating mechanism through the entire cycle of movement thereof, means located below the free ends of said plate carriers and movable synchronously with said elevating mechanism to shift a plate on said plate carriers from the ascending to the descending stretch of said mechanism during the stationary interval of said movement, and means movable synchronously with said elevating mechanism for feeding a plate to said plate carriers.

12. Apparatus for drying wet plates embodying elevating mechanism suitably mounted and driven to have intermittent movement and having ascending and descending stretches, plate-carriers permanently mounted at one edge on said elevating mechanism and carried therewith through the cycle of movement thereof, shifting means movable synchronously with the elevating mechanism to shift a plate from the ascending to the descending stretch of plate carriers during the stationary interval of said intermittent movement and delivery means also movable synchronously with said elevating mechanism for discharging a plate from said plate carriers during said interval.

13. Apparatus for drying wet plates embodying, in combination, a conveyor chain mounted to extend substantially in a vertical direction and having substantially parallel ascending and descending stretches, a series of plate carriers connected at one edge to and carried by said chain through its complete cycle of movement and extending horizontally on said ascending and descending stretches.

to engage the bottom surfaces only of wet plates, means for shifting a plate from the ascending stretch to the descending stretch comprising a plate-shifting device at the outer edge of the plate-carriers for initially shifting plates edgewise and a secondary plate shifting device arranged between the ascending and descending stretches for continuing said edgewise movement to cause the plate to seat on a plate-carrier on the descending stretch.

In witness whereof, we have signed our names to the foregoing specification.

CHARLES WAGNER.

AUGUST HORMEL.
